COAL CAR FOR TOY TRAIN

Earl F. Fribley, Auburn, Ind., assignor to Auburn Rubber Company, Inc., Auburn, Ind., a corporation

Filed Apr. 2, 1959, Ser. No. 55,327

Term of patent 7 years

(Cl. D34—15)

FIG. 1 is a side elevational view of a coal car for toy train, showing my new design.

FIG. 2 is a top plan view of that shown in FIG. 1.

FIG. 3 is a front elevational view thereof.

FIG. 4 is a rear elevational view thereof.

I claim:

The ornamental design for a coal car for toy train, as shown.
